US00D711826S

(12) **United States Design Patent**
Yonishi et al.

(10) **Patent No.:** US D711,826 S
(45) **Date of Patent:** ** Aug. 26, 2014

(54) **RECHARGEABLE BATTERY**

(71) Applicant: **Sony Corporation**, Tokyo (JP)

(72) Inventors: **Kiyoshi Yonishi**, Tokyo (JP); **Atsuhiro Kumagai**, Tokyo (JP); **Takeshi Ichimura**, Tokyo (JP); **Yuki Okuno**, Tokyo (JP)

(73) Assignee: **Sony Corporation**, Tokyo (JP)

(**) Term: **14 Years**

(21) Appl. No.: **29/462,492**

(22) Filed: **Aug. 5, 2013**

Related U.S. Application Data

(63) Continuation of application No. 29/442,045, filed on Nov. 21, 2012, now Pat. No. Des. 687,777.
